CHAIR

Jacques S. Guillon, 501 Lansdown, Westmount,
Quebec, Canada

Continuation-in-part of design application Ser. No. 4,198,
Oct. 7, 1966. This application Aug. 19, 1968, Ser. No.
13,176

Claims priority, application Canada Apr. 9, 1966

Term of patent 14 years

Int. Cl. D6—01

U.S. Cl. D15—1

FIG. 1

FIG. 2

FIGURE 1 is a front perspective view of a chair showing my design; and

FIGURE 2 is a rear perspective view thereof.

The dotted line showing of cushions is for illustrative purposes only.

This application is a continuation-in-part of applicant's application Serial No. D.4,198, filed October 7, 1966, and abandoned in favor of this application.

I claim:

The ornamental design for a chair, as shown and described.
